UNITED STATES PATENT OFFICE.

CLARENCE M. STINER, OF NEW YORK, N. Y., ASSIGNOR TO THE AUTO TICKER-TAPE DISPLAY COMPANY, A CORPORATION OF NEW YORK.

ATTACHMENT FOR PRINTING-TELEGRAPHS OR OTHER STRIP-DELIVERING APPARATUS.

SPECIFICATION forming part of Letters Patent No. 735,311, dated August 4, 1903.

Application filed February 11, 1901. Serial No. 46,765. (No model.)

To all whom it may concern:

Be it known that I, CLARENCE M. STINER, a citizen of the United States, residing at the city of New York, in the borough of Manhattan and State of New York, have invented certain new and useful Improvements in Attachments for Printing-Telegraphs or other Strip-Delivering Apparatus, of which the following is a full, clear, and exact description.

10 In certain forms of printing-telegraphs, such as the well-known "ticker" for printing stock reports and other intelligence, the printed matter appears upon one side of a continuous narrow ribbon of paper or tape which is automatically drawn from a reel, printed, and then ejected from the instrument into a box, basket, or other receptacle from which it may be withdrawn for perusal; but since the printing is done in what is practically but a 15 single line a few minutes' work on the part of the machine will suffice to use up a considerable length of tape, and it is therefore often necessary to handle many yards of the tape in order to find reports which have been printed 20 but a comparatively short time, and in the case of machines located in public places the tapes, owing to frequent and in most cases careless handling, soon become confused and tangled 25 masses, readable only near the instrument, 30 and early reports being completely hidden and practically inaccessible.

The object of the present invention is to produce a device which, coöperating with an ordinary ticker or similar instrument, shall be adapted to receive the tape as it emerges 35 from the instrument and arrange the same upon a suitable receiver in a compact and orderly manner printed side up, so that the printed matter may be easily read.

40 Broadly, the invention consists of the combination, with a printing-telegraph or other instrument or machine in which a continuous tape or sheet is printed upon or otherwise treated and then ejected, of a receiver and means whereby said tape or sheet will be arranged upon said receiver neatly and compactly and in a regular, uniform, or definite order, so that printed matter or other impressions upon the surface of the tape or sheet 45 50 will be exposed to view in such manner that

the same may be conveniently examined or observed.

More specifically, the invention consists of the combination, with a printing-telegraph or the like, of a receiver for said tape adapted to move step by step across the path of movement of the tape as the latter leaves the instrument, means for separating the tape into strips of predetermined length, means for feeding such strips to the receiver, and means for moving the receiver after each strip has been fed thereto, whereby said strips will be applied to the receiver in parallel lines, so that printed matter thereupon can be read line after line, like the printed page of a book.

My invention comprehends the use of a receiver of any desired shape and of any desired dimensions either in length or width; but in practice it will probably be found preferable in most cases to employ a number of small receivers or a receiver divided into a plurality of sections rather than a single continuous receiver. One advantage of a plurality of receiver-sections is economy of space, and in the embodiment of my invention herein disclosed such arrangement has been adopted.

In the embodiment referred to a plurality of empty receiver-sections are compactly arranged in a group or pile of small compass to one side of the line of movement of the tape as it issues from the instrument, said movement in this case being in a substantially horizontal plane. A motor adapted to operate at intervals is arranged to engage the receiver-sections, withdraw them successively from the group or pile referred to, and move them step by step transversely to the path of movement of the tape, a suitable guiding-channel being provided for the tape to direct the same from the instrument onto the surface of a receiver-section. A device for cutting or severing the tape will be located between said channel and the receiver-sections in line with the tape. A receiver-section having been withdrawn from the group or pile into operative relation with the tape will remain stationary during the operation of the ticker or other instrument until a predetermined length of the tape has been laid upon it.

the surface of said section, whereupon the motor will be released. The release of the motor will cause the knife to descend, severing the tape at the edge of the receiver-section 5 and causing the section itself to be advanced one step, carrying the severed strip with it, and presenting another portion of its surface to the tape for a fresh strip. As the several sections become filled with strips of 10 tape they may be successively transferred to another part of the device and again arranged in a compact group or pile.

One important aim of my invention is to 15 keep at all times a considerable portion of the latest news or intelligence received over the instrument exposed to view in readable form, and since it is also desirable that the earlier news be of easy access provision is made whereby the contents of any of the filled sections, even after the same have been transferred to the group or pile of such filled sections, may be readily exposed to view at any time.

20 In the accompanying drawings I have illustrated an organization of mechanisms which I 25 wish to be understood as representative of only one of the many forms in which my invention may be embodied, and while I shall hereinafter describe such embodiment in detail I do not limit myself in any way whatsoever to the structural details as they herein appear or to any other specific construction.

Figure 1 represents a plan view of my invention. Fig. 2 is an end elevation of Fig. 35 1 looking in the direction of arrows 22. Fig. 3 is a section on line $x-x$ of Fig. 1 looking in the direction of arrows 22. Fig. 4 is a section on line $y-y$ of Fig. 1 looking in the direction of arrows 33. Fig. 5 is a detail illustrating the operation of a rocking lever and pawl. Fig. 6 is a detail illustrating the manner of exposing to view the contents of one of a group or pile of receiver-sections. Fig. 40 45 5 is a sectional view of what is shown in Fig. 6 with an additional slide partly drawn out. Fig. 8 is a detail of the knife and knife-operating mechanism, and Fig. 9 is a detail of the motor.

50 Referring to the drawings by letters and numerals, A represents a casing, within which the working parts of the device are supported and housed.

B is a platform located in chamber b at one end of said casing, and C a similar platform 55 located in chamber c at the other end thereof. Platforms B and C are supported by vertical shafts or columns B' and C', which shafts are toothed, as shown, and engaged by spur-wheels b' and c', respectively. Spur-wheels b' and c' are engaged by a common drive-gear D, which is mounted upon a shaft E. A pulley E', to which a weight E² is attached, is also secured to said shaft.

Extending across the space between the two 60 65 chambers b and c and near the upper portions thereof are tracks, guides, or ways d d. Platform B is designed to carry a charge or

supply of receiver-sections, (represented by the numerals 1, 2, 3, 4, &c.,) which sections are piled one upon the other in the manner best 70 shown in Fig. 4. The function and the details of construction of these receiver-sections will appear hereinafter and need not be considered now. For the present it will suffice to state that in the regular operation of the machine these sections, beginning with the topmost, will be transferred successively across the guides or tracks d d and piled regularly, one upon the other, upon the platform C, the arrangement being that the bottom of the topmost section on platform B will be in line with said guides or tracks as well as in line with the upper surface of the platform C or the upper surface of a pile of receiver-sections that may lie upon said platform. 80 85

The function of the weight E² is to keep the topmost of the pile of receiver-sections on platform B pressed against the under side of the cover a of the chamber b, in which position it may be engaged by the transferring devices, to be described hereinafter, and withdrawn from the pile. Whenever a section shall have been wholly withdrawn from said pile, weight E² will act and carry the next succeeding section against the cover a. Now 95 if the pull of the weight on shaft E were a constant factor the friction between cover a and the receiver-sections would be increased every time a section was withdrawn from platform B, since the removal of each section 100 would lighten the pile and correspondingly lessen the resistance to said weight. Accordingly I have divided the weight into a plurality of members e e, spaced apart and separately attached to the pulley-cord, as indicated in Fig. 4. As the weight descends these members will one by one come to rest upon a suitable support, as a², and the pull upon shaft E, and the consequent upward thrust of the platform B, be gradually lessened; but since the receiver-sections are removed from platform B only to be transferred to platform C the weight upon the latter will be increased as fast as that upon the former is decreased, which fact will also tend to produce 110 115 friction between the cover and the receiver-sections, it being understood that downward pressure on platform C will exert upward pressure on platform B. To counteract this effect, I provide a second weight F and attach it to the pulley E' in such manner that it will exert a pull thereon opposite in effect to that of weight E². Weight F, like weight E², will be made up of a plurality of members f f, spaced apart and separately attached to the 120 pulley-cord f'; but in this case the members of the weight will normally be at rest upon a suitable support a², as shown, and lifted one by one as the pulley is rotated, thereby gradually adding resistance to the gradually-increasing downward thrust of platform C. Preferably weight F will be attached to pulley E' by a cord containing some slack, so 125 130 that it will not be brought into action until

an appreciable number of receiver-sections have been transferred to platform B.

The details of the receiver-sections are clearly shown in Figs. 4, 6, and 7, wherein 5 they will be seen to each consist of a supporting-tray s and a sliding pan s' , mounted therein, the said pan being adapted to be drawn out from the tray in the manner indicated in Figs. 7 and 8, but prevented from 10 being wholly withdrawn by the pins s^2 , working in slots s^3 . The under sides of the trays are provided with one or more rows of teeth or notches s^4 , extending from back to front, while the upper surfaces of the pans are laid 15 out in a series of parallel grooves s^5 , extending from side to side and having overhanging edges s^6 .

G represents a printing-telegraph instrument or ticker of the usual or any preferred 20 construction, which is mounted upon a frame g , secured to the side of casing A. The details of this instrument forming no part of the invention are not illustrated.

H represents the tape, which, as usual, is 25 drawn by the instrument from a reel, (indicated at H'), passes between the printing-rolls or type, (not shown,) emerges at h , and then enters the guiding-channel h' , the tape being pushed along said channel by the same force 30 which draws it into the instrument for printing. Between the instrument and the reel I locate a light wheel or drum K, of definite diameter and carrying a tripper k , the tape being caused by idler k^2 to pass over a considerable 35 portion of the periphery of said drum in order to rotate the latter.

Within the channel h' is a hinged leaf i , adapted to rest upon the tape and overcome any tendency the latter may have to rise out 40 of the channel at this point. The channel, it will be seen, approaches the casing A at a point between the chambers b and c preferably nearer the former and occupies the same horizontal plane as that of any receiver- 45 section that may be resting upon the tracks or guides $d d$, it being the function of said channel to direct the tape into the grooves s^5 of such receiver-sections. The sections are moved at intervals a distance equal to the 50 width of a groove, so that each groove may be successively brought into line with the channel h' and receive the tape. The direction of movement of the tape is at right angles to that of a receiver-section as the latter passes along the guides $d d$, and at the 55 point of intersection of the two paths of movement I locate a tape-cutting device P.

J represents a motor of suitable character. In the present embodiment of my invention 60 it is a weight-actuated shaft j , geared to a train of wheels $j' j''$, &c., said train including an escape-wheel l , having a notch l' therein. A detent l^2 normally engages notch l' and serves to lock the motor against movement, 65 the detent being carried upon one end of a rod M. The other end of rod M extends to the drum K and is adapted to be engaged by

the tripper k once in each rotation of the drum, the effect being to raise the detent and release the motor, the detent riding upon the 70 periphery of the escape-wheel l until the latter has made one complete rotation, when it will again engage the notch and stop the motor.

Rod M carries a second detent m , adapted 75 to engage, successively, each of the notches m' in a wheel m^2 in the motor-train. The number of notches m' will be one less than the number of teeth s^4 on the under side of the receiver-sections. For instance, if there are 80 eight teeth s^4 the wheel m^2 will be divided into eight equal spaces and notched at seven of such spaces. Wheel m^2 is adapted to make one-eighth of a rotation while escape-wheel l makes one complete rotation, the notches on 85 the former being arranged so as to be presented to detent m at the same moment that notch l' is presented to detent l^2 . The effect of this will be that escape-wheel l will be permitted to make six successive single rotations, 90 the two detents rising and falling together, and then a double rotation as the unbroken portion m^5 of the periphery of wheel m^2 comes into play and holds detent m , and consequently detent l^2 , in raised position during a 95 quarter-turn of said wheel m^2 .

N represents one or more cams secured to the shaft n of one of the wheels of the motor, and N' one or more rocking levers pivoted at n' and spring-pressed against said cams. 100 Each lever N' will be provided with a pawl n^2 at its upper end, said pawls being adapted to engage the teeth or notches s^4 on the under side of the receiver-sections. Geared to shaft n is a parallel shaft o , the outer end of which 105 carries a crank o' , engaging a slot p in the lower end of the vertically-reciprocating cutter-bar P, whose cutting edge is at p' .

Assuming the parts to be in the positions shown in Figs. 1, 3, and 4, the operation will 110 be as follows: Each impulse of the ticker will unreel a portion of the tape and cause the drum K to be rotated and the end h^3 of said tape advanced through the first groove s^5 in receiver-section 1 a distance equal to the 115 length of said unreeled portion. This action will be continued, the receiver-section meanwhile remaining stationary, until the drum K shall have rotated sufficiently to carry the tripper k into engagement with the rod M, 120 whereupon said rod will be tripped and the motor released in the manner before described. At the time of the release of the motor the tape will have reached the farther end of the first groove in receiver-section 1. The length 125 of each groove is approximately equal to the circumference of the drum K, so that when the instrument has fed out a strip of tape equal in length to a groove the drum will have made one complete rotation and the tripper k brought 130 into operation. The release of the motor therefore will be coincident with the filling of a groove with tape. Each operation of the motor will effect one revolution of the shaft n as

well as one revolution of shaft n , the latter serving to actuate the tape-severing devices in a manner clearly indicated in Fig. 9. The first half of the revolution of shaft n will carry 5 cam N from the position shown in Fig. 4 to that shown in Fig. 5, and so allow spring r to act and throw the upper ends of levers N' from right to left, Fig. 3. This will cause pawls n^2 to pass between receiver-sections 1 and 2 10 of the group or pile in chamber b and engage the underside of the uppermost section of said group in the manner indicated in Fig. 5, the trays 5 being cut away at s^7 for the passage of the pawl. The second half-revolution of shaft 15 n serves to restore the lever N' to its original position and causes said uppermost receiver-section to be advanced a distance equal to the width of a groove, carrying the severed strip of tape with it and moving the next succeeding 20 groove into alignment with the channel h' ready to receive the tape at the next feeding operation of the ticker or other instrument. This operation will be continued until the uppermost section (or section 1) has been wholly 25 withdrawn from the pile in chamber b and rests upon the guides d in the space between the platforms B and C , whereupon the weight E^2 will act and raise platform B and carry the 30 next section 2 into position to be engaged by the pawls n^2 . At this stage of the operation it will be necessary to allow the motor to run long enough to actuate the pawls twice in order to advance the receiver-section 2 far enough to carry the first groove thereof into 35 alignment with channel h' . This will be accomplished by arranging the wheel m^2 in such manner that the unbroken part m^5 of its periphery will act on detent m just after a receiver-section shall have been wholly withdrawn from chamber b . Section 2 then being 40 advanced step by step in the manner already described will shove section 1 along ahead of it, so that by the time section 2 has been wholly withdrawn from the group or pile section 1 45 will have been transferred to the top of the pile on platform C and section 3 raised to a position within reach of the pawls n^2 .

It will be observed that by the general arrangement described a considerable portion 50 of the latest printed matter issued by the ticker or other instrument will be exposed at the top of the apparatus in convenient reading position. In order to read earlier news, it will only be necessary to withdraw the sliding 55 pans s' from their respective trays in the manner illustrated in Figs. 6 and 7, the side of the casing or frame A being open at a^5 to admit of such withdrawal. The trays are supported upon each other and their edges are high 60 enough above their respective sliding pans to space the latter apart and relieve the same of the weight of the other trays and pans. If the pans rested directly upon each other, the friction between them would probably be too 65 great for their ready withdrawal.

Having described my invention, I claim—
1. In combination with a printing-telegraph

or other machine adapted to treat a surface of a continuous ribbon, tape or strip of material, and then eject the same, a receiver for 70 said material, and means whereby said material will be arranged in a regular, uniform or definite order upon said receiver, with its treated side exposed to view throughout its length. 75

2. In combination with a printing-telegraph or other instrument adapted to print upon one side of a continuous ribbon, tape or strip of material and then eject the same, a receiver, and means whereby said material will be arranged upon said receiver so as to be readable throughout its length. 80

3. In combination with a printing-telegraph or other machine adapted to feed out a continuous ribbon, tape or strip of material, a receiver for said material, and means for arranging the material upon said receiver in regularly succeeding separate lines. 85

4. In combination with a printing-telegraph or other machine adapted to feed out a continuous ribbon, tape or strip of material, of a receiver for said material, and means for depositing said material in regularly succeeding separated sections thereon. 90

5. In combination with a printing-telegraph or other machine adapted to feed out a continuous ribbon, tape or strip of material, of a receiver for said material, and means whereby the latter may be applied to the receiver in separated parallel sections. 95 100

6. In combination, a movable receiver, a printing-telegraph or other machine adapted to feed out a continuous ribbon, tape or strip of material, and to deliver the same to said receiver, and means whereby said material may be separated into sections of suitable length as it is delivered to the receiver. 105

7. In combination, a printing-telegraph or other machine adapted to feed out a continuous ribbon, tape or strip of material, means whereby said material will be separated into sections of suitable length, and means whereby said sections will be arranged in regular sequence upon said receiver. 110

8. In combination with a printing-telegraph or other machine adapted to eject a continuous ribbon, tape or strip of material, a receiver for said material, means whereby said material will be separated into sections of suitable length, and means whereby said sections will be applied to said receiver in parallel rows or lines. 115 120

9. In combination, a receiver, a printing-telegraph or other machine adapted to eject a ribbon, tape or strip of material and deliver the same to said receiver, means for severing said material after a predetermined portion thereof has been delivered to said receiver, and means whereby the position of said severed portion will be shifted after such 125 delivery. 130

10. In combination with a printing-telegraph or other machine adapted to eject a ribbon, tape or strip of material, of a receiver

for said material, means for moving the receiver transversely to the direction of movement of the material, and means for cutting said material into strips.

5 11. In combination with a printing-telegraph or other machine adapted to eject a ribbon, tape or strip of material, of a receiver for said material, means for moving said receiver intermittently in a direction transverse to the direction of movement of said material, and means for cutting said material into strips.

12. In combination, a receiver, a printing-telegraph or other machine adapted to eject 15 a ribbon, tape or strip of material and deliver the same to said receiver, means for severing said material after a predetermined portion thereof has been delivered to said receiver, and means for moving said receiver after 20 such delivery, whereby the position of the severed portion may be shifted.

13. In combination, a printing-telegraph or other instrument adapted to treat a surface of a ribbon, tape or strip of material and then 25 eject the same, a receiver provided with parallel grooves, means whereby said receiver may be moved intermittently and each groove thereof presented successively to the material, and means for severing the tape after a 30 predetermined length thereof has been applied to a groove.

14. In combination, a printing-telegraph or other instrument adapted to treat a ribbon, tape or sheet of material and then eject the 35 same, a receiver for said material consisting of a plurality of receiver-sections, means whereby each of said sections may be moved successively step by step, and means whereby said material may be applied to said moving receiver-sections.

15. In combination, a printing-telegraph or other instrument adapted to treat a ribbon, tape or sheet of material and then feed out the same, a receiver for said material consisting of a plurality of receiver-sections, means 45 whereby each of said sections may be moved

successively, step by step, transversely to the movement of the tape, means whereby said tape may be applied to said sections in separate strips of suitable length, and means 50 whereby said receiver-sections may be arranged in a group or pile after the tape has been applied thereto.

16. In a printing-telegraph, a movable platform adapted to support a pile or group of receiver-sections, means whereby said sections may be withdrawn successively and from said platform and moved step by step across suitable tracks or ways, and means whereby a tape or sheet of material may be fed to said 60 sections while the latter rest upon said tracks or ways.

17. In a printing-telegraph, a movable platform adapted to support a pile or group of receiver-sections, a second movable platform, 65 means whereby the said receiver-sections may be removed successively from the first platform and grouped or piled upon the second platform, and means for feeding strips of material to said sections in transit.

70 18. In a printing-telegraph, a movable platform adapted to support a pile or group of receiver-sections, a second movable platform, means whereby the said receiver-sections may be removed from the first platform and 75 grouped or piled upon the second platform, means for feeding strips of material to said sections in transit, and means for maintaining an approximate balance between the two platforms.

80 19. In a printing-telegraph, a receiver-section comprising a supporting-tray and a sliding pan mounted therein, the said pan having a surface adapted to receive and retain strips or sheets of material fed thereto by suitable means.

In witness whereof I subscribe my signature in presence of two witnesses.

CLARENCE M. STINER.
